UNITED STATES PATENT OFFICE.

JOHN P. BROPHY, OF CLEVELAND, OHIO.

TRAFFIC SIGNAL.

Application filed September 16, 1925. Serial No. 56,720.

This invention, relating, as indicated, to a new and improved traffic signal, refers more particularly to improvements in an illuminated signaling device which is adapted to 5 be mounted at street intersections to indicate direction of traffic movement. The principal object of the invention is to provide a device of this character which is simple in construction, efficient in use, and one 10 in which the various incandescent lamps may be very easily replaced.

The present novel device essentially consists of a plurality of lights which are reflected through the conventional red and 15 green lens. My invention also has for its object to provide, in connection with these red and green lens, an annular band portion at the front of the indicating device which is illuminated at all times. This band 20 is preferably red in color and serves to more clearly indicate the position of the signaling device, the same being illuminated even when the red and green signals are momentarily changing from one to the other. To the accomplishment of the foregoing and related 25 ends, said invention, then, consists of the means hereinafter fully described and particularly pointed out in the claims.

The annexed drawings and the following 30 description set forth in detail certain mechanism embodying the invention, such disclosed means constituting, however, but one of the various mechanical forms in which the principle of the invention may be used.

35 In said annexed drawings:—

Fig. 1 is a front elevation of the device per se; Fig. 2 is a horizontal cross-sectional view taken on the line 2—2 of Fig. 1; and

Fig. 3 is a view on reduced scale showing 40 one method of mounting the present device.

The device generally consists of an annular or drum-shaped casing 10, in which is carried a plurality of incandescent lamp bulbs 11, 12 and 13 for a purpose to be hereinafter described. The forward end of the casing 10 is closed by a lens plate 14, the latter being held in a peripheral groove 15, formed in the casing 10, by a removable ring 16. The rear end of casing 10 is normally closed by a cover 17 which is attached to said casing at one side by a hinged connection 18 and at the other side by a bolt 19. The bolt 19 is swivelly mounted between lugs 20 provided on the casing and 50 engages between the forked portion of other lugs 21 on the cover. A nut 22 is utilized

to lock the parts together, it being necessary to only partially unscrew said nut when it is desired to open the cover 17, which construction is best illustrated at the top of 60 Fig. 2.

Carried interiorly of the casing 10, adjacent the front end thereof, is a frame 23 which serves, as will be described, to carry the lights 11 and 12 in proper position behind the red and green portions 24 and 25, respectively, of the lens plate 14. This frame is held centrally of the casing by a plurality of inwardly projecting screw members 26. The inner end of such screws is 70 formed conical, as at 27, to engage with tapered surfaces 28 provided on integral lugs 29 of the frame 23, and serve to move the entire framework toward the lens plate 14 as well as to position it centrally within the 75 casing 10. In the front edge 30 of the frame 23 is located suitable packing material 31 which, when engaged with the lens 14, acts to prevent the escape of light beyond that portion of the frame 23. The particular 80 shape of the opening, or red and green colored portions 24 and 25, is of no moment, the same being shown in Fig. 1 as oval in shape, with one above the other. The frame 23 is divided into two light chambers 32 and 33 by a partition 34, which latter part is 85 illustrated as being removably mounted in a slotted portion 35 of the frame 23. It will be seen from Fig. 2 that the lights 11 and 12 are carried respectively, in chambers 90 32 and 33, and that the illumination from one, as from the light 11, is prevented from showing through the portion 24 by the partition 34.

Mounted centrally of the cover 17 is the 95 light 13 which is utilized to illuminate an annular rim portion 37 formed in the lens 14 at its outer edge. This portion 37 is here shown and described as comprising a lens red in color which is intended to be illuminated at all times. The inner face 38 of the cover 17 may be provided with a reflecting surface to convey the light from the light 13 around the outer edge of the frame 23.

As hereinbefore mentioned, this invention 105 contemplates the provision of means adapted to facilitate the replacement of the lights 11, 12 or 13. Inasmuch as the socket of each of these lights and the mounting means are identical, only one will now be described. 110 The socket indicated at 39 may be of any conventional design and is mounted at its

base in an annular plug or base member 40, which is secured in a sleeve 41 by fingers 42. These fingers 42 are shown as being struck inwardly from the sleeve 41 to engage 5 with the sides of member 40. The sleeve 41 is adapted to be slidably received in an enlarged opening 43, which is of sufficient size to accommodate the diameter of the light 13. Means, as set screws 44, are provided in the 10 hub portion 45 in the cover 17 to fix ring 41, together with the light 13, in desired position. The other lights 11 and 12 are similarly mounted in the frame 23, screws 45 and 46 being provided there to hold said 15 lights in place, it being obvious that the cover 17 is to be swung about its hinge 18 to permit access to the lights 11 and 12.

It will be apparent from the above that I have accomplished the objects primarily 20 stated and that I have provided a traffic signaling device of improved character, which combines direction indicating devices together with a continuously illuminated danger signal, i. e., the signal consists of 25 red and green reflecting portions and an annular illuminated red colored portion. The entire device may be conveniently mounted by lateral bars 50 attached at one end by bolts 51 to opposite sides of the casing 10. The other ends of the bars, as shown 30 in Fig. 3, are secured to clamp members 52 adapted to engage around a standard or support 53. The members 52 are made adjustable to provide for the proper height 35 displacement of the present signaling device.

Other modes of applying the principle 40 of my invention may be employed instead of the one explained, change being made as regards the mechanism herein disclosed, provided the means stated by any of the following claims or the equivalent of such stated 45 means be employed.

I therefore particularly point out and 45 distinctly claim as my invention—

1. A traffic signalling device comprising

a casing, a single lens on the front of said casing, a continuous red band about the marginal portion of said lens providing an attention centering area therefor, a pair of 50 red and green colored areas on said lens spaced from each other and positioned within and spaced from said marginal red colored band, and providing traffic directing signals, an opaque area covering all the intervening surface of said lens, means for continuously illuminating said red colored marginal band and means for alternatively illuminating said red and green colored areas.

2. In a device of the character described, 60 the combination of an annular casing, a lens mounted at one end thereof, a hinged cover attached to the other end, a light-carrying frame positioned interiorly of said casing, 65 said frame being smaller than the inside diameter, of the casing and having separate light chambers therein, means for supporting said frame against the inside surface of said lens, and a light mounted in said cover adapted to reflect light between said frame 70 and casing.

3. In a device of the character described, 75 the combination of a casing, a cover for the rear end of said casing, means removably mounting said cover on said casing, a lens on the front of said casing, a lamp socket receiving aperture centrally of the cover of said casing and adapted to receive a lamp through the rearward end thereof, a lamp carrying frame positioned within said casing, means mounted in the marginal portions of said casing for pressing said frame against the inner surface of said lens, a plurality of lamp receiving apertures in the 80 rear wall of said lamp carrying frame, said aperture being open at the rearward portions to receive the bases upon which said lamps are supported.

Signed by me, this 14th day of September, 85 1925.

JOHN P. BROPHY.
